(57) **CLAIM**

The ornamental design for a projector lamp, as shown and described.

DESCRIPTION

FIG. 1 is a bottom view of the projector lamp;

FIG. 2 is a top view thereof;

FIG. 3 is a right side view thereof;

FIG. 4 is a left side view thereof;

FIG. 5 is a front view thereof;

FIG. 6 is a rear perspective view thereof; and,

FIG. 7 is a rear perspective view of the projector lamp.

The dashed lines in FIG. 7 are for the purpose of illustrating environmental structure and form no part of the claimed design.
